UNITED STATES PATENT OFFICE.

JOHN KALAF, JR., OF META, MISSOURI.

MUSICAL INSTRUMENT.

1,417,174.

Specification of Letters Patent. Patented May 23, 1922.

Application filed April 15, 1921. Serial No. 461,463.

To all whom it may concern:

Be it known that I, JOHN KALAF, Jr., a citizen of the United States, residing at Meta, in the county of Osage and State of Missouri, have invented a new and useful Musical Instrument, of which the following is a specification.

This invention aims to provide a musical instrument of the violin type, which, being simply made, may be turned out at comparatively small expense, thereby doing away with the high grade cabinet work required in the making of an ordinary violin body.

Another object of the invention is to provide an instrument of the sort mentioned, which will give forth a strong and strident tone, the instrument being of peculiar utility in the production of dance music and under other conditions where loudness and volume of tone are prime requisites.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the drawings:—

Figure 1 shows in plan, an instrument constructed in accordance with the invention; Figure 2 is a side elevation of the instrument; Figure 3 is a section on the line 3—3 of Figure 2.

The instrument comprises a body 1 which, if desired, may be made solid, out of a single board or piece of material, thereby avoiding the expense incident to shaping and assembling a box-like body of ordinary construction. A neck 2 is assembled with the body 1, the numeral 3 marking a tail piece of common form. The head 4 may be shaped like a mandolin head, if desired, and may be provided with a well known form of worm and pinion means 5 for tensioning the strings 6 and 7, which extend between said means 5 and the tail piece 3.

The strings may be made in various ways. Assuming that the common violin tuning in fifths is resorted to, the G string, denoted

by the numeral 7, may be a wound string, the other strings 6 being double, like the strings of a mandolin, and being of metal, should the operator so desire. The double metal strings 6, clearly increase the volume of sound and the loudness of the tone. The strings 6 of each pair are tuned in unison.

Superposed upon and secured to the body 1 is a casing comprising a tubular member 8 having a bottom 80, the tubular member being surmounted by a cap 9 of annular form, the cap being held in place by securing elements 10. The cap 9 serves to hold a resonant diaphragm 11 on the tubular member 8 of the casing, a washer 12 being interposed between the cap and the diaphragm, in order to prevent the edge of the diaphragm from being crushed, should it be found desirable to construct the diaphragm from celluloid or like material, which is somewhat fragile.

The numeral 14 designates a main bridge, across which the strings 6 and 7 pass, the main bridge serving to take up much of the strain produced by the tension in the strings. The main bridge 14 has a relatively long leg 15 which rests on the body 1, and a shorter leg 16 which rests on the cap portion 9 of the casing. Since the leg 16 rests on the casing, some of the vibration is carried into the casing and thence into the diaphragm 11.

A fulcrum strip 17, having a sharpened upper edge, is superposed upon the cap 9 of the casing. The numeral 18 denotes an oscillatory auxiliary bridge, which, if desired, may be merely the common violin bridge now in use. The auxiliary bridge 18 is supported upon a foot 19 having a depending end 20 resting on the diaphragm 11. The strings 6 and 7 pass across the auxiliary bridge 18. The foot 19, together with the auxiliary bridge 18 may be shifted transversely of the fulcrum strip 17 whereon the foot is pivotally mounted, the object being to regulate the pressure of the end 20 of the foot 19 on the diaphragm 11. Since the auxiliary bridge 18 is pivotally mounted by means of the foot 19 on the fulcrum strip 17, the bridge will vibrate freely, responsive to the strings 6 and 7, and the vibrations will be transmitted to the diaphragm 11.

The numeral 21 denotes a horn, comprising a funnel-shaped socket 22 having an annular end 23 passing through an opening 24 in the body 1 and fitting closely in the

bottom 80 of the casing. A bell 25 is provided, and has an angular end 26 fitting tightly but adjustably in the socket 22. Ordinarily, the bell 25 extends upwardly and projects forwardly, at one side of the instrument, as shown in Figures 1 and 2, that, since the end 26 of the bell is received adjustably in the socket 22, the bell may be disposed at any desired angle. The vibrations of the diaphragm 11 are transmitted to the air column in the horn 21, the result being a strong and loud tone, emanating from an instrument of simple construction.

What is claimed is:—

- 15 1. An instrument of the string type comprising a body; a sound amplifier on the body, said amplifier comprising a diaphragm and a casing; a main bridge having its ends resting, respectively, on the body, and on the casing of the amplifier independently of the diaphragm; an oscillatory bridge engaging the diaphragm; and a string extended across the bridges.
- 20 2. An instrument of the string type comprising a body; a casing on the body and comprising a diaphragm and a casing; an

oscillatory auxiliary bridge engaging the diaphragm; a main bridge; means for supporting the main bridge independently of the diaphragm; and strings extended across the bridges, certain of the strings being double, and the double strings comprising parts which are tuned in unison.

3. An instrument of the string type comprising a body; a casing on the body and including a diaphragm; a main bridge resting at one end on the body and resting at its other end on the casing independently of the diaphragm; an auxiliary bridge mounted to oscillate on the casing independently of the diaphragm, and bearing at one end on the diaphragm; a horn carried by the body and communicating with the casing; and a string engaged with both bridges.

In testimony that I claim the foregoing 45 as my own, I have hereto affixed my signature in the presence of two witnesses.

JOHN KALAF, JR.
